ENGINE SCAVENGING AND FUELING MECHANISM

Filed March 21, 1929

Owen H. Spencer
Inventor

UNITED STATES PATENT OFFICE

OWEN H. SPENCER, OF INDIANAPOLIS, INDIANA

ENGINE SCAVENGING AND FUELING MECHANISM

Application filed March 21, 1929. Serial No. 348,906.

This invention relates to a combined air and fuel control for internal combustion engines and the prime feature of the invention is the provision of means in connection with the ordinary type valve operating rod for controlling the admission of scavenging of air to the cylinder of the engine in cooperation with the admission of fuel by the ordinary tappet valve.

10 A further feature of the invention is in so arranging the air control that the air will be cut off incident to the admission of fuel to the cylinder.

15 A further feature of the invention is in so timing the air controlling means that the fuel controlling valve will be practically closed before air is admitted to the cylinder, thereby obviating the possibility of forcing the charge of fuel from the cylinder during 20 the interim of charging the cylinder with fuel.

A further feature of the invention is in so arranging the admission of air to the cylinder that it will act as a scavenger for the 25 interior of the cylinders of the engine.

Other objects and advantages will be hereinafter more fully set forth and pointed out in the accompanying specification.

The accompanying drawing which is made 30 a part of this application, is partly diagrammatic.

The figure is a vertical sectional view thru the cylinder and crank case of an engine, with the positions of different parts shown 35 by full and dotted lines.

Referring to the drawing the numeral 1 indicates the cylinder of an internal combustion engine, having the usual form of fuel poppet valve 2 therein through which fuel 40 is injected under pressure from any suitable source and 3 indicates the usual form of crank case connected with the cylinder 1.

Vertically slidable in the cylinder 1 is a piston 4, which operates in the usual manner 45 with a crank shaft 5, the usual form of connecting rod 6 being provided between the piston 4 and the crank shaft 5.

The poppet valve 2 is operated thru the medium of a rocker arm 7 and a spring 8, 50 as is usual, said rocker arm 7 being controlled

by means of a rod 9, which is in turn operated thru the medium of a tappet 10 and a cam 11, the latter being mounted on a shaft 12, operated by a gear 13, which is in turn operated from a gear 14 on the cam shaft 12. 55

The lower end of section A of the rod 9 and the upper end of the tappet 10 meet within air receiving chamber 15 into which air is forced from any suitable source, the upper portion of the chamber 15 communicating 60 with the interior of the cylinder 1, thru a port 16. The passage of the air thru the port 16 is controlled by a piston type damper 17 on the rod section A, which cooperates with an elongated valve seat 18 within the 65 chamber 15, said seat being positioned between the inlet opening 19 and the inlet port 16, the valve 17 having free passage into the seat 18. By providing the elongated seat 18, the valve 17 may have considerable upward 70 and downward movement with the valve still remaining in closed relation with the seat.

The piston 4 is shown in its full downward position in full lines, as when the fuel is being taken into the cylinder, the poppet 75 valve 2 also being shown substantially approaching its closed position by full lines, with the valve 17 still in substantially full closed position in full lines, but approaching open position.

As the piston proceeds on its upward or what is to be its compression stroke, the port 16 is first closed by it, as indicated by dotted lines 21, then the exhaust port 20 is likewise closed as indicated by the dot-and-dash lines 85 22.

As the piston starts from its lower position, the tappet valve 2 has started to close. The position of the tappet valve at the time the upper end of the piston closes the port 16, being indicated by dotted lines 23, and 90 is completely closed, as indicated by dot-and-dash lines 24, when the piston has closed the exhaust port 20, or as indicated by dot-and-dash lines 22.

When the piston 4 is in the position indicated by full lines, the damper 17 will be 95 in closed position as shown by full lines, but begins to open as the piston rises and will assume the position indicated by dotted lines 25, when the piston reaches the position indi- 100

cated by dotted lines 21, and will have moved to full open position as indicated by dot-and-dash lines 26, by the time the piston has reached the dot-and-dash position 22, the respective positions of the tappet 10 and cam 11 during the aforesaid movements of the piston and valves, being likewise indicated by dotted and dot-and-dash lines, respectively.

10 Although the damper 17 is now in full open position, no air can enter the cylinder, as the piston forms a closure for the port 16, but when the piston has been forced downwardly by the firing of the engine and the port 16 is 15 uncovered, the air will enter the cylinder with more or less force, thus quickly emptying the cylinder of the exhaust and acting as a scavenger for cleansing the cylinder and piston head of impurities and foreign particles.

20 By placing a baffle 27 on the upper end of the piston 4, the force of the air entering the cylinder will be directed upwardly in the upper portion of the cylinder against the valve 2 and serve to cool same as well as 25 the adjacent parts. A large portion of the air will remain, and become heated in the cylinder and will commingle with the charge of fuel next drawn into the cylinder, thus greatly enriching the fuel mixture and imparting a greater explosive force to the mixture without increasing the quantity of fuel charge.

By arranging the valves and operating parts therefore in the manner shown and 35 described, one of the valves will always be opened incident to the closing of the other, these operations being automatic, and it will likewise be seen that by introducing the air in the manner shown, it will act as a scavenger for cleansing and cooling the interior of 40 the cylinder, as well as enriching the charge of fuel.

The said section A is slidably fit in the upper wall portion of the chamber 15 and serves 45 to guide the damper 17, while the rod 9, proper, likewise is loosely guided in said upper wall portion for flexibility in operation with the rocker arm 7.

While the description and drawing illustrates in a general way certain instrumentalities which may be employed in carrying the invention into effect, it is evident that many modifications may be made in the various details without departing from the scope 55 of the appended claims, it being understood that the invention is not restricted to the particular example herein described.

I claim as my invention:

1. A combined air and fuel control for engines, a cylinder, a fuel intake port in the top of the cylinder, an air intake port in the lower wall of said cylinder, poppet-valves cooperating with each of said ports, a rod mounted on said air valve, a stem mounted 60 on said fuel valve, a rocker connecting said 65

rod and stem, said fuel valve being open when said air valve is closed and closed when said air valve is open.

2. A combined air and fuel control for engines, comprising a cylinder, a fuel intake port in the top of the cylinder, a valve co-operating with said port for controlling the admission of fuel to the cylinder, a port in the lower wall of said cylinder, a valve for controlling said latter port, and a single rod 70 mechanism for operating both of said valves and arranged for opening one valve when the other valve is closing and vice versa.

In testimony whereof, I have hereunto set my hand on this 16th day of March, 1929, 80 A. D.

OWEN H. SPENCER.
